INVENTOR

UNITED STATES PATENT OFFICE.

WILLIAM A. SALTER, OF KANSAS CITY, MISSOURI.

MULTIPLE-TURRET-TOOL HOLDER.

1,426,778.

Specification of Letters Patent. Patented Aug. 22, 1922.

Application filed July 6, 1920. Serial No. 394,226.

To all whom it may concern:

Be it known that I, WILLIAM A. SALTER, a citizen of the United States, residing at Kansas City, in the county of Jackson and 5 State of Missouri, have invented certain new and useful Improvements of Multiple-Turret-Tool Holders, of which the following is a specification.

My invention relates to a tool holder for 10 use on lathes and other machines used in machine shops, and has for its object the holding of a number of edged cutting tools, any one of which can be without changing the setting of the others, be brought into position for use against the work in hand, and 15 locked into position for use.

To attain this end generally speaking, my invention consists of a central supporting member, that is bolted rigidly to the tool 20 rest of the carriage of the lathe or machine, a tool carrier revolving around the supporting member, an operating and locking bolt, connected between the supporting member and the tool carrier, and adjustable means 25 by which the tool carrier can be set and locked at different heights, at its working positions.

As my invention contemplates the application 30 of these improvements to the most highly organized mechanism of multiple turret tool holders of the present day, it is obvious the details of organization and construction herein shown, may be varied when they include well known equivalents there- 35 for, with departing from the scope of my claims.

The subject matter claimed is hereinafter set forth in the claims at the end of this specification.

40 In the accompanying drawings, I have represented a multiple turret tool holder embodying all of my improvements in the best way now known to me, as is necessary to illustrate the subject matter claimed.

45 Some of these improvements however may be used without the others, and in tools of different details in construction from the one herein shown.

Fig. 1 is a sectional side view of the as- 50 sembed tool holder.

Fig. 2 is a top view of the supporting member and the tool carrier.

Fig. 3 is a side and front view of the operating locking member or bolt.

55 Fig. 4 is a top view of the top end of the supporting member at line 1—2, and show-

ing the positions of the operating locking member and the operating handle.

In the practice of my invention, the supporting member B, is made with a long 60 cylindrical shaft having a flange for a base, that sets on the rest, of the carriage of the machine, on which it is mounted. This flange is bored and carries the finding pin "G" that registers with the holes H' in the 65 tool carrier A. The cylindrical portion of the supporting member B is bored throughout its length with a hole through which passes the bolt E engaging with the slot block F, and by means of which it is rigidly 70 fastened to the lathe carriage. This cylindrical portion of the supporting member is also bored at the top end to receive the locking spring K, and in the same section is slotted to receive the locking operating bolt 75 C, and at the lower end of the locking spring a certain cross section is planed away to receive the operating handle D, which is fastened to it by means of the screw I.

The tool carrier A, is preferable in its 80 main section of a square form, to carry the tool bits and having a cylindrical section at its upper end. The square section has preferably rectangular grooves cut on all of its four sides to receive the cutting tool bits, 85 which are held in positions for work by means of the screws J. It is also bored on its axial line, to make a close accurate slip fit with the supporting member B, and its flange, and is bored also in its square portion with the holes H' all of which are of equal distance from the axial center of this tool holder and register with the finding pin G. These holes H' are threaded from the top nearly throughout their length and receive the threaded adjusting screws H with 90 which they engage. The tool holder A also at its top end of the cylindrical section has a number of beveled notches A" cut that engage with the locking bolt C, the location of 95 these notches being such that when the finding pin G registers with one of the holes H', a corresponding locking notch on its beveled side engages with the beveled side of the locking bolt C' of the locking bolt C, the 100 crowd between the notch and beveled lug bringing the pin G firmly against the side of the hole H', and holding the tool carrier A rigidly and without movement until released. There are as many locking notches 105 at the upper end of the tool carrier as there are holes H' or tool bit positions.

The locking bolt C at its lower end has an extending lug that works in a groove machined in the central part of the tool carrier A, for lifting the carrier block off the finding pin G; as shown in Fig. 1 and Fig. 3. It also has near its central section a locking lug C' that is beveled on one side, and engages with the locking notch A'' of the tool carrier A. It also has a hole cut in its central part C'' to engage with the operating handle D, that is carried by the supporting member B.

In operation pressing down on the operating handle D, first lifts the locking lug C' from engagement with the locking notch A'' and then lifts by means of the lug at the lower end of the locking bolt C engaging with the groove in the central part of the tool carrier A, this tool carrier A is lifted from the finding pin G, and is free to revolve to any position desired by the person using it. And after revolving the tool carrier until the proper cutting tool bit is in position for use, releasing the operating handle D, allows the tool carrier to descend, the finding pin G being on the proper hole H' and the spring K automatically forces the locking bolt C downward until the locking lug C' engages with the locking notch A'' and rigidly holds the tool carrier A in position.

Raising and lowering the adjusting screws H, varies the distance which the finding pin G can enter the holes H' and corresponding varies the height at which the tool carrier is locked for use, the ends of the screws H at

their lower terminals, being designed to engage with the upper end of the finding pin G, and providing means for vertical adjustable setting of the cutting tool edges.

I claim as my invention and desire to secure by Letters Patent:

1. In a multiple turret tool holder, the combination of a supporting member, a revolving tool carrier member having locking recesses with registry holes, a registry stop pin carried by the supporting member engaging with the registry holes in the tool carrier and the adjustable stop screws therein, an operating locking bolt, and means whereby the tool carrier is locked by wedging action between one side of the stop pin and the beveled side of the locking bolt engaging with a locking recess.

2. In a multiple turret tool holder, the combination of a supporting member carrying a stop registry pin, a revolving tool carrier having registry holes with adjustable height screws therein locking notches, an operating locking bolt having a bevel side, and operative means whereby the beveled section of locking bolt engages with the locking notches of the tool carrier.

In testimony whereof, I have signed my name to this specification in the presence of two subscribing witnesses.

WILLIAM A. SALTER.
